UNITED STATES PATENT OFFICE.

EDWARD G. SIM AND ROBERT H. BISHOP, OF SMITHFIELD, COUNTY OF MIDDLESEX, ENGLAND.

TROUSERS-STRETCHER.

SPECIFICATION forming part of Letters Patent No. 367,559, dated August 2, 1887.

Application filed March 14, 1887. Serial No. 230,848. (No model.)

To all whom it may concern:

Be it known that we, EDWARD GEORGE SIM and ROBERT HODGES BISHOP, both of 42 Clothfair, Smithfield, in the county of Middlesex, England, have invented certain new and useful Improvements in Apparatus for Stretching Trousers, of which the following is a specification.

In trousers-stretchers as at present most commonly constructed the trousers are secured on the outside in two places by clamps, which are pushed apart by a screwed rod or other mechanical means, and tension is thereby applied to the trousers to take out creases, &c. There are, however, objections to the use of clamps, the most important of which is that they make marks on the trousers.

Now, the present invention consists in a novel and very simple and inexpensive device, hereinafter described and claimed, which is to be applied within the leg of the trousers, and by which the objections to the use of clamps will be overcome.

Our stretcher is composed of a length of spring-steel wire or analogous metal bent to the shape substantially as shown in the drawing, which represents a side view of a stretcher. This form resembles substantially a double outline profile of the letter H. The ends of the wire are secured together by a clip, C, and the wire then constitutes a combination of two bars, A A', which conform, respectively, to the back and front of the longitudinally-folded leg

of the trousers, and two springs, B B', connecting the ends of said bars and nearly meeting at the middle of the length thereof. The front bar, A, is represented as curved at a to fit the lower part of the front of the trousers.

To introduce the stretcher into the leg of the trousers, it will only be necessary to grasp with the hand the two spring portions B B' of the wire on both sides of the middle b and press them together to contract the width of the stretcher and then insert the apparatus into the upper part of the trousers-leg and afterward push it down to the required position at or near the bottom. The stretcher when thus inserted will distend and stretch the trousers-leg and thereby take out the creases.

What we claim as our invention, and desire to secure by Letters Patent, is—

A trousers stretcher composed of one length of wire bent to a form substantially like that of a double outline profile of the letter H, and constituting a combination of two bars, A A', and two springs, B B', which connect the ends of said bars and nearly meet at the middle of the length thereof, substantially as herein set forth.

EDWARD G. SIM.
